INVENTOR

Ben Grozow
Warren B. House,
His ATTORNEY

UNITED STATES PATENT OFFICE

BEN GROZOW, OF KANSAS CITY, MISSOURI

GARMENT HANGER

Application filed October 3, 1931. Serial No. 566,629.

My invention relates to improvements in garment hangers.

One of the objects of my invention is to provide a novel garment hanger around which garments supported thereon may be folded thereon and be held thereby from being wrinkled or creased when stored in a suit case, Gladstone traveling bag, trunk or other receptacle, and which may also be used for hanging garments in the usual manner from a hook or other support in a closet or other storing place.

The novel features of my invention are hereinafter fully described and claimed.

15 In the accompanying drawing which illustrates the preferred embodiment of my invention and modifications thereof,

Fig. 1 is an elevation of the preferred embodiment of my improved garment hanger, 20 with the U shaped member shown in the upper non-operative position.

Fig. 2 is a view of the garment hanger shown in Fig. 1, partly in side elevation and partly in section, with the U shaped member 25 shown in its operative position.

Fig. 3 is an end elevation of the same, with the U shaped member in its operative position.

30 Fig. 4 is a view similar to Fig. 1, showing a modification of my invention.

Fig. 5 is a plan view of the hanger shown in Fig. 4, shown mounted in a suit case, a portion only of which is shown, with the 35 garments folded around the hanger.

Fig. 6 is a side elevation of still another modification of my invention.

Fig. 7 is an end elevation of the hanger shown in Fig. 6.

40 Fig. 8 is a view partly in side elevation and partly in section of another modified form of my invention.

Fig. 9 is an enlarged perspective view of one of the attaching clips shown in Fig. 5.

45 Similar characters of reference designate similar parts in the different views.

In the forms of my invention shown in Figs. 1 to 6, a piece of wire, rod or similar material has a horizontal portion 1 adapted 50 to have folded over it and to support a gar-

ment, such as a pair of trousers 2, shown in dotted lines in Figs. 1 and 4.

The wire has two end portions 3 which respectively extend upwardly from the ends of the horizontal lower portion 1. Said wire 55 also has two transverse garment supporting portions 4 which respectively incline upwardly and cross each other at a place of juncture 5 in the middle of the hanger, at which place the crossed portions 4 may be 60 fastened together, as by welding or soldering. The portions 4 are adapted to support a garment, such as a coat 7, shown in dotted lines in Figs. 1 and 4.

Two upper portions 8 extend respectively 65 in opposite directions from the upper ends of the inclined portions 4 parallel with the lower portion 1.

The portions 8 at their outer ends are upwardly turned and respectively provided 70 with eyes 9 adapted to respectively releasably engage two tongues 10 of two clips 11 fastened to the inner side of a receptacle, such as a suit case 12, Fig. 5.

A supporting member comprising a hook 75 13 has an eye 14 encircling the inclined portions 4 at their place of crossing. This hook 13 may be employed when the hanger is to be hung in the usual manner in a closet or other place.

80 As shown in Figs. 1, 2 and 8, two wooden rollers 15 may be respectively mounted on the upper portions 8.

85 For holding folded the sleeves and lapels of a garment 7, a U shaped member is provided, the arms 16 of which, as shown in Figs. 1 and 2, are flat bars pivoted respectively at one set of ends on the upper portions 8 at the outer ends of the rollers 15.

The lower ends of the arms 16 are respectively fastened, as by screws 17 to opposite ends of a wooden cylinder 18, which forms the transverse part of the U shaped member.

In the form shown in Figs. 4 and 5, the U shaped member comprises a single piece of 95 wire bent into U form, the arms 19 of which are provided respectively with two eyes 20 which are pivotally mounted on the upper portions 8.

100 After the garments, such as 2 and 7 are

mounted respectively on the portion 1 and the inclined portions 4, the U shaped member is swung to the position shown in Fig. 2, following which the garments are folded 5 around the garment hanger over the rollers 15 and around the cylinder 18. The garments with the hanger on which they are folded may then be placed in a suit case 12, or other receptacle with the eyes 9 engaging the tongues 10 of two clips 11 mounted as described in the receptacle.

In the form shown in Figs. 4 and 5, the U shaped member is swung from the position shown in Fig. 4 in solid lines to the position 15 shown in dotted lines in said figure, thus holding the garments preparatory to their being folded around the upper portions 8 and the horizontal part 1, as shown in Fig. 5.

As shown in Fig. 6, a ring 21 may encircle 20 the inclined portions 4 at their place of crossing, and to this ring may be removably attached a hanger 22 of the usual construction.

In the form shown in Fig. 8, the construction corresponds to the garment supporting 25 parts shown in Figs. 1 and 2, with the omission of the U shaped member, and in the horizontal lower portion upon which the trousers are folded being a cylinder 23 into the ends of which are inserted the turned in 30 portions of the end portions 3. A transverse brace 24 connects the end portions 3 above the cylinder 23.

Other modifications of my invention, within the scope of the appended claims, may be 35 made without departing from the spirit thereof.

I claim:

1. A garment hanger comprising a lower horizontal garment supporting portion, two 40 end portions extending respectively upwardly from the ends of said horizontal portion, two transverse garment supporting portions extending respectively from the upper ends of said end portions to a place of juncture, two upper portions extending in opposite directions from said place of juncture parallel with said lower portion, and a U shaped member having its arms respectively pivoted to 45 said upper portions so as to be swung to and from a position in which its transverse part will be adapted to bear against a garment supported by said transverse portions.

2. A garment hanger comprising a lower horizontal garment supporting portion, two 55 end portions extending respectively upwardly from the ends of said horizontal portion, two garment supporting portions inclining upwardly from the upper ends of said end portions and crossing each other at a place 60 of juncture, two upper portions extending respectively in opposite directions from the upper ends of said inclined portions parallel with said lower horizontal portion, and a U shaped member having its arms respectively 65 pivoted to said upper portions so as to be

swung to and from a position in which its transverse part will be adapted to bear against a garment supported by said inclined portions.

In testimony whereof I have signed my 70 name to this specification.

BEN GROZOW.
